FIG. 6.

INVENTOR:
Henry D. Mandeville,

BY
F. C. Fischer,
ATTORNEY.

UNITED STATES PATENT OFFICE.

HENRY D. MANDEVILLE, OF KANSAS CITY, KANSAS.

WASHING-MACHINE.

1,220,135.

Specification of Letters Patent. Patented Mar. 20, 1917.

Application filed March 8, 1915, Serial No. 12,719. Renewed February 14, 1917. Serial No. 148,592.

To all whom it may concern:

Be it known that I, HENRY D. MANDEVILLE, a citizen of the United States, residing at Kansas City, in the county of Wyandotte and State of Kansas, have invented 5 certain new and useful Improvements in Washing-Machines, of which the following is a specification.

My invention relates to improvements in 10 washing machines, and the objects of the invention are to provide a machine from which the interior parts may be removed, so that all parts may be cleansed and dried and kept in a sanitary condition; one that can be 15 placed upon a stove, so that the clothes may be boiled while being washed and thus hasten the washing process; one that will thoroughly wash garments and other articles without tearing the same; and one in which 20 the most soiled garments may be cleansed at a minimum expenditure of time and labor.

In the accompanying drawings, which illustrate the invention:

Figure 1 is a vertical central section of a 25 washing machine constructed in accordance with my invention.

Fig. 2 is a broken plan view of the machine with its lid removed.

Fig. 3 is a side elevation of the machine.

30 Fig. 4 is a plan view of the machine.

Fig. 5 is an irregular broken section on line V—V of Fig. 1.

Fig. 6 is an elevation of two brushes employed in carrying out the invention.

35 In carrying out the invention, I employ a suitable tub 1 provided at its central portion with a vertically-arranged cylinder 2, rigidly secured to the tub bottom 3 by lugs 4.

40 5 designates a stationary shaft arranged within the cylinder 2 and provided at its upper end with a circular track 6, upon which the rollers 7 of a spider 8 travel.

The spider 8 is rotatably-mounted upon the upper portion of the shaft 5, which extends 45 through the lid 9 of the tub, and has a thumb screw 10 for securing said lid 9 upon the tub. In addition to the rollers 7 the spider 8 is provided with rollers 11, which travel against the underside of an annular track 12 and prevent the rollers 7 from rising off the track 6.

The spider 8 is rotated by a bevel gear 13 fixed thereto and intermeshing with a bevel gear 14, extending through an opening 15 in the lid 9 and fixedly-mounted upon a shaft 16, journaled in bearings 17 and provided at

its outer end with a hand-wheel 18 having a laterally projecting handle 19, so that it may be rapidly rotated in one direction when but few clothes are in the tub. The hand-wheel 60 18 is also provided with radial handles 20, so that both hands may be employed in rotating said wheel 18 when the tub contains a large number of clothes. The radial handles 20 also provide convenient means for imparting alternate rotary motion to the spider 8 through the intermediacy of the intervening gearing.

The spider 8 is provided with a plurality of depending brushes 21 which constitute 70 the agitator for stirring up the clothes within the tub. The cores 22 of the brushes 21 are removably but firmly secured to the spider 8 by U-bolts 23. Said brushes 21 contact with stationary brushes lining the bottom and side of the tub 1 and also surrounding the cylinder 2.

The bottom brushes 24 are radially arranged and spaced apart, as disclosed by Fig. 2. The brushes 25 and 26 lining the 80 side of the tub and surrounding the cylinder 2, respectively, are vertically arranged with their adjacent sides abutting each other as disclosed by Fig. 6. The backs of the brushes 25 and 26 have longitudinal registering recesses 27, so that the water in the tub may flow freely between said brushes.

The brushes 24, 25 and 26, like the brushes 21 are removable, so that they may be exposed to the air and sun for the purpose of 90 drying said brushes and keeping them sanitary. This arrangement of the brushes also permits the tub 1 to be maintained in a thoroughly sanitary condition by exposure to the air and sun.

95 In placing the brushes 24, 25 and 26 in the tub 1, the brushes 24 are first placed in position upon the bottom of the tub where they are held by flanged rings 28 and 29 slipped down against the bottom of the tub 100 and arranged to fit against the side of said tub and embrace the cylinder 2, respectively, as disclosed by Fig. 1. The brushes 26 are then placed around the cylinder 2 against which they are held by the ring 29 and a 105 ring 30, which latter is slipped over the upper end of said cylinder 2. The shaft 5 is then inserted in the cylinder 2, so that the circular track 6 will overlap and hold the ring 30 firmly upon the upper ends of the 110 brushes 26. The spider 8 is then placed in position over the upper portion of the shaft

5 and the brushes 25 are placed against the inner surface of the side of the tub 1, where they are reliably held by the ring 28 and a flanged ring 31 slipped over the upper ends 5 of said brushes and the upper edge of the tub 1, as disclosed by Fig. 1. The ring 31 is then reliably held in place by the lid 9, which is provided at one side with a door 32, so that articles to be washed may be 10 placed in the tub or removed therefrom without removing the entire lid 9.

The lid 9 and the door 32 are firmly held down upon the ring 31 by clips 33. The door 32 is secured to the lid 9 by hinges 34 15 and is reinforced by a strip 36 secured thereto. The lid 9 is reinforced by a strip 36 firmly secured thereto and provided with a bearing 37 for the adjacent end of the shaft 16.

20 With the foregoing arrangement of brushes, it is evident that when the agitator is actuated the articles will be thoroughly rubbed over the bristles of said brushes, and the water will be forced through said 25 articles until they are thoroughly cleansed. In order that the water may thoroughly circulate through the cylinder 2, slots 38 are formed therein for the entrance and discharge of water passing through the recesses 30 27 in the longitudinal sides of the brushes 26.

From the foregoing description, it is apparent that I have produced a sanitary washing machine in which garments and other articles may be quickly and thoroughly 35 cleansed at a minimum expenditure of time and labor, and while I have shown and described the preferred form of my invention, I reserve the right to make such changes in the construction, combination, 40 and arrangement of parts as properly fall within the spirit and scope of the claims.

Having thus described my invention, what I claim and desire to secure by Letters Patent, is:

45 1. In combination with a tub having a central cylinder therein, a shaft in the cylinder projecting thereabove, a circular track secured to the shaft and seating on the upper end of the cylinder, a spider journaled 50 on the shaft above said track and having rollers which ride on the track, rollers borne by the spider and extending thereabove, a lid, a circular track on the lid engaged with the last named rollers, means to

rotate the spider and clothes engaging 55 means borne by the spider and depending therefrom.

2. In combination with a tub having a central vertical member therein, two series of vertical brushes abutting said member 60 and the interior of the tub sides respectively, a series of brushes on the tub bottom, a ring surrounding the top of said member and having a depending flange which engages the top ends of the brush backs which 65 abut said member, a ring surrounding the top of the tub and having a depending flange which engages the top ends of the brush backs which abut the tub sides, and a pair of rings one of which surrounds the 70 bottom of said member and the other of which is disposed adjacent the tub sides, said pair of rings having vertical flanges which receive the lower ends of the respective series of vertical brush backs, and having horizontal flanges which engage over the respective ends of the bottom brush backs and clothes engaging means operable 75 in the space below the brushes.

3. In combination with a tub having a 80 central vertical hollow member the latter provided with spaced vertical slots, a series of vertical brushes arranged in abutting relation about said member and having vertical registering side recesses which register 85 recesses register with said slots, and clothes engaging means operable within the tub.

4. In combination with a tub having a central vertical member therein, two series 90 of vertical brushes abutting said member and the interior of the tub sides respectively, a series of brushes on the tub bottom, removable unitary means engaged with each of the upper ends of the brush backs that 95 abut said member, removable unitary means engaged with each of the upper ends of the brush backs which abut the tub sides, and a pair of removable unitary means which engage both the lower ends of the vertical 100 brush backs and the adjacent ends of the bottom brush backs respectively.

In testimony whereof I affix my signature in the presence of two witnesses.

HENRY D. MANDEVILLE.
